UNITED STATES PATENT OFFICE

151,236

DESIGN FOR A SMOKER'S STAND OR THE LIKE

Philip S. Harper, Chicago, Ill., assignor to Harper-Wyman Company, Chicago, Ill., a corporation of Illinois

Application June 24, 1946, Serial No. 130,983

Term of patent 14 years

(Cl. D85—2)

To all whom it may concern:

Be it known that I, Philip S. Harper, a citizen of the United States, residing at Chicago, in the county of Cook and State of Illinois, have invented a new, original, and ornamental Design for Smoker's Stand or the like, of which the following is a specification, reference being had to the accompanying drawing, forming part thereof.

Fig. 1 is a side elevational view of a smoker's stand or the like embodying my new design;

Fig. 2 is a top plan view thereof with the ash receiver removed;

Fig. 3 is a horizontal cross sectional view taken along the line 3—3 of Fig. 1; and

Fig. 4 is a perspective view thereof.

The essential features of my design reside in the portion shown in solid lines.

I claim:

The ornamental design for a smoker's stand or the like, as shown and described.

PHILIP S. HARPER.
